O. W. Hallendale.

UNITED STATES PATENT OFFICE.

BRENSON DOUD, OF PERU, INDIANA.

FENCE.

SPECIFICATION forming part of Letters Patent No. 396,735, dated January 29, 1889.

Application filed September 12, 1888. Serial No. 285,212. (No model.)

To all whom it may concern:

Be it known that I, BRENSON DOUD, a citizen of the United States, residing at Peru, in the county of Miami and State of Indiana, have invented certain new and useful Improvements in Fences; and I do hereby declare the following to be a full, clear, and exact description of the invention, such as will enable others skilled in the art to which it appertains to make and use the same.

My invention is an improvement in fences; and my said invention consists in the combination, in a fence, with the vertical posts, longitudinal rails, and vertical wires for suspending said rails between the posts which wire is secured around the foot of the post, then crossed back and forth around the end of each rail and over the top of the post, and secured by staples at each side of the rails, of a series of short wires secured at the ends of the rails, passed around the post, and secured thereto by staples, as and for the purposes as will be hereinafter more fully described and form the subject-matter of the appended claim.

In carrying out the details of my invention I proceed as follows, reference being had to the accompanying drawings, forming a part hereof, and in which drawings—

Figure 1 is a vertical side elevation of a fence-panel and a portion of an adjacent panel constructed according to my invention, and Figs. 2 and 3 detail sectional views.

The letter A designates the posts, which are to be set in the ground at any suitable distance apart; and B, the rails, which extend longitudinally between the posts, and to which they are secured in the following manner:

C is a double wire, or wire of two strands, which, after being passed around the foot of the post, as at c, and secured at each side by

staples b, is then crossed back and forth around the rails B, as at D. After this wire C has been crossed upon the top of the top rail it is carried across the top of the post A and there secured by a staple, as at a. It is then crossed upon the top of the top rail of the next succeeding panel, and then carried downward and around the end of each of the rails in said second panel in a similar manner as upon the first panel to the ground, after which it is again passed around the foot of the post A and secured by staples, as at b'. In addition to crossing the wire C back and forth around each rail, it is secured at each side of said rails B by staples, as at e; and to secure the panel at its center a short wire, E, is secured by a staple, d, to the outer end of the rails B, which wire is then passed around the post and secured upon each side thereof by staples d'. 60

By the arrangement of the parts as here shown the panel is securely held between the posts at the top, bottom, and center thereof, and a simple and durable yet cheap and easily-constructed fence is formed, not liable to be easily injured, and sufficiently strong to resist breaching stock.

I claim—

The combination, in a fence, with the posts A, rails B, and vertical wires C, said wires C being secured around the foot of the post, then crossed back and forth around the end of each rail and over the top of the post, and secured by staples e at each side of the rail, of the short wires E, secured at the ends of the rails by staples d, passed around the posts A, and secured thereto by staples d', as described, for the purposes specified.

BRENSON DOUD.

In presence of—

J. D. OATES,
THOS. FILDES.
